GAS RANGE

John E. Chambers, Shelbyville, Ind.

Application June 22, 1936, Serial No. 86,477

4 Claims. (Cl. 126—42)

My invention relates to gas ranges, and it is my principal object to decrease the possibility that any of the valves controlling the supply of gas to the various burners of the range will be inadvertently left open to permit the escape of gas.

In carrying out my invention, I prefer to apply it to that type of gas range in which the control members regulating the supply of gas to the various burners are rather closely grouped at the front of the range, although my invention in its broader aspects is not limited to this particular arrangement. Associated with each burner-control member I provide a signal member which occupies a normal position when gas is shut off from the associated burner but which must necessarily be displaced from such normal position whenever gas, in any quantity, is being supplied to the burner. When the burner-control members are grouped, I prefer to arrange the signal members so that they are all in alignment with each other when in their respective normal positions and to so construct each signal member that it will be moved out of alignment with the other signal members whenever gas is supplied to its associated burner.

The accompanying drawing illustrates an embodiment of my invention: Fig. 1 is a fragmental front elevation of the gas range showing the preferred arrangement of burner-control members and signal members; Fig. 2 is a vertical section on an enlarged scale on the line 2—2 of Fig. 1 showing a burner control member and its associated signal member in the positions they occupy when no gas is being supplied; and Fig. 3 is a view similar to Fig. 2 showing the signal member moved to the position it occupies whenever its associated valve is about to be opened.

The gas range 10 to which my invention is applied is preferably of the cabinet type shown in Fig. 1, and the control members 11 which regulate the supply of gas to the various burners of the range are grouped on the front wall of the range. Conveniently, the control members 11 are arranged to swing in vertical planes about axes in alignment with each other.

Associated with each control member 11 is a vertically movable signal member 12, such signal members preferably being so arranged that when in normal position they will be horizontally aligned with each other. The signal members 12 are interconnected with the respectively associated control members 11 to insure that whenever a control member is moved to turn on the gas a corresponding signal member 12 will be moved

out of alignment with the other signal members. The control member second from the right in Fig. 1 is indicated as moved to turn on the gas; and, as is clearly evident from the drawing, the associated signal member 12 is lowered so that it is out of alignment with the remaining signal members.

Conveniently, the various control members and signal members are supported from the rear wall of a casing 15 which is secured against the inner face of the front wall 16 of the range. For each control member 11 and its associated signal member 12, there is provided a stationary bracket 17 which extends forwardly through a vertical slot 18 in the front wall 16. At its outer end, the bracket 17 is pivotally connected, as by means of a pin 19, with the control member 11. Desirably, the control member 11 includes a handle portion 20 which, when the control member is in normal position, extends downwardly generally parallel to the front wall 16.

Conveniently, gas is supplied to the various burners of the range from a manifold 22 which extends horizontally parallel to the front wall 16, each burner being connected to the manifold 22 by a conduit 23 including a valve 24. Each of the control members 11 is operatively interconnected to the movable element of a corresponding valve 24, this connection being shown as effected through the medium of a link 25 which is secured at one end to the operating arm 26 of the valve 24 and which extends forwardly through a suitable opening in the rear wall of the casing and through the slot 18. For interconnecting the front end of each link 25 with the associated control member 11, I prefer to provide a trunnion 27 which is pivotally mounted in the control member on a horizontal axis between the handle-portion 20 and the front wall of the range, such trunnion being provided with a transverse screw-threaded hole for the reception of the screw-threaded end of the link 25.

Attached to each of the brackets 17, as by means of a pivot pin 30 located in rear of the front wall 16, is a swinging member 31 which has two vertically spaced arms 32 and 33 extending forwardly through the slot 18. The upper arm 32 carries the signal member 12, which may be in the form of a small plate bearing indicia indicating the position in the range of the associated burner. The lower arm 33 and the control member 11 have co-operating provisions which insure that whenever the control member 11 is moved to turn on the gas the signal member 12 will be depressed from its normal position.

As is clear from Figs. 2 and 3, each control member 11 is provided with a flange 35 having an inner surface concentric with the pin 19 about which the control member 11 swings. The 5 swinging member 31 is so arranged that the end of the arm 33, which has the upwardly and outwardly extending arcuate shape indicated at 33', may either abut against the end of the flange 35, as indicated in Fig. 2, or may be moved downward 10 so as to clear the flange 35 when the control member 11 is swung in a counterclockwise direction to open the associated valve 24. As indicated, the swinging member 31 is biased in a counter-clockwise direction toward the position 15 shown in Fig. 2 by means of a compression spring 37 which acts between the arm 33 and the rear wall of the casing 15 and which is held in place by a tongue 38 formed on the arm 33. Movement of the swinging member 31 under the influence of 20 the spring 37 is conveniently limited by an abutment 39 which engages the rear wall of the casing 15.

When all the gas valves 24 of the range are closed, each of the control members 11 occupies the position shown in Fig. 2 and in full-lines in 25 Fig. 3. The various springs 37 hold the respectively associated swinging members 31 at the limit of their counter-clockwise movement with the outer ends 33' of the arms 33 in abutting relation with the flanges 35 and the signal members 12 in substantial alinement with each other. When it is desired to light any burner, the associated signal member 12 is first depressed to the 30 position illustrated in Fig. 3. This movement of the signal member causes the swinging member 31 to move in a clockwise direction from the position shown in Fig. 2 and carries the free end 33' of the arm 33 out of abutting relation with the flange 35, whereupon the control member 11 may 35 be swung to or toward the dotted-line position illustrated in Fig. 3 to open the associated valve 24. In any valve-opening movement of the control member 11, the end of the flange 35 is carried inwardly over the free end 33' of the arm 33 and thus prevents the associated spring 37 from 40 moving the swinging member 31 to its normal position. As a result, so long as any valve 24 is open, even to the slightest extent, the associated signal member 12 will be depressed from its normal 45 position and will be disposed out of alinement with the remaining signal members 12. This disposition of any depressed signal member is readily apparent and indicates that the associated valve 24 is at least partially open.

50 Any signal member which has been once depressed and held in depressed position by the flange 35 of the associated control member 11 remains in depressed position until the control member is returned to normal position and the associated valve 24 closed. When that occurs, the flange 35 clears the free end of the arm 33 and permits the spring 37 to restore the swinging member 31 to its normal position.

55 With the arrangement illustrated in the drawing, it is possible to so dispose the parts of the device that, with the thumb of the operator depressing the signal member 12 the fingers of the same hand can grasp and move outwardly the handle portion 12 of the associated control member 11. Downward movement of each signal member 12 under the influence of thumb-pressure 60 applied to its upper surface may be limited by engagement of the lower surface of the arm-end 33' with the pin 19, as illustrated in Fig. 3. The 65 arcuate shape of the arm-end 33' permits the

control member 11 to swing outwardly, as indicated in dotted-lines in Fig. 3, without interference between the flange 35 and the body of the arm 33.

In the preferred arrangement, shown in the drawing, the arm-end 33' and the end of the flange 35 engage on surfaces which are disposed radially relatively to the pin 19 and substantially normal to the line joining their point of engagement with the axis of the pin 30. As a result, any force applied to the control member 10 to move it in a valve-opening direction from normal position has no tendency to displace the swinging member 31; and, therefore, as long as any signal member is in its normal position accidental valve-opening movement of the associated control member becomes impossible.

I claim as my invention:

1. In a gas range having a front wall, a manifold disposed in rear of said wall and parallel thereto, burner-supply pipes leading rearwardly from 20 said manifold at spaced intervals, a valve in each of said pipes, a plurality of valve-controlling members disposed in front of said wall and mounted for swinging movement about a common axis parallel to said manifold, operative connections between said members and the respective valves, a movable element associated with each of said control members, each of said movable elements being supported for pivotal movement about an axis in rear of said wall and including a portion extending forwardly through said wall, and means biasing said element toward a normal position, said element and control member having co-operating provisions for preventing valve-opening movement of said control member when said element is in normal position and for maintaining said element displaced from its normal position whenever the control member is out of the position it occupies when the valve is closed.

2. The invention set forth in claim 1 with the addition that each of said control members has a handle portion extending downwardly from its axis, the forwardly extending portion of the associated movable element being disposed above the axis of the control member in position to be 45 engaged and moved from normal position by the thumb of an operator whose fingers grip the handle portion of the control member.

3. The invention set forth in claim 1 with the addition that the forwardly projecting portions 50 of said movable elements are in substantial alinement when in their respective normal positions.

4. In a gas range having a front wall, a burner-supply pipe located in rear of said wall, a valve in 55 said pipe, a valve-control member connected to said valve and mounted for swinging movement about an axis located in front of said wall, a locking and indicating element pivotally supported in rear of said wall on an axis parallel to that of said control member and having a portion projecting through said front wall, an arcuate flange on said control member concentric with the axis thereof, an arcuate tongue on the forwardly projecting portion of said element, and means 60 biasing said element to a normal position in which the end of said tongue normally engages the end of said flange to prevent said control member from moving to open said valve, said element being movable about its axis to displace said tongue inwardly and out of alinement with the end of said flange to permit said control member to move to open said valve.
